ELECTRONIC INDICATING DEVICE

Charles N. Kimball, East Orange, N. J., and Edward W. Wilby, Westerleigh, N. Y., assignors to Radio Corporation of America, a corporation of Delaware

Application October 27, 1937, Serial No. 171,254

6 Claims. (Cl. 250—27.5)

Our invention relates to electron discharge devices, more particularly to such devices useful as visual indicators of voltage and having a fluorescent electrode which is rendered luminous and 5 has the appearance of a pattern of light which changes in response to the change in the magnitude of the applied voltages, a device of this character being particularly suitable for indicating resonance of apparatus responsive to radio 10 frequency currents and voltages. The present application is a continuation in part of our application, Serial No. 112,462, filed November 24, 1936 and assigned to the Radio Corporation of America.

15 There has been disclosed, and claimed, in U. S. Patent 2,051,189 of H. M. Wagner, patented August 18, 1936, an electron ray indicator tube conventionally described as the 6E5 type. Briefly, such a tube comprises an envelope having within 20 it a cathode provided with two emission sections. One of the emission sections is surrounded by amplifier electrodes comprising a grid and anode and the other is surrounded by the tuning indicator elements. The indicator elements comprise 25 a control electrode and a dish-shaped anode coated on its inner surface with fluorescent material. The control electrode is connected to the amplifier anode, and the amplifier section input electrode or grid is connected to a source of signal-derived direct current voltage. When maximum signal is tuned in, the luminous portion of the plate, or target, is of a maximum width. With minimum, or no signal the electronic shadow cast by the control electrode on the coated 30 anode or target is a maximum. In a receiving system equipped with automatic volume control (AVC), the grid of the indicator tube amplifier section is connected to the AVC voltage source.

35 Such a 6E5 type tube is satisfactory when used in signalling systems producing direct current voltages for the indicator tube input grid which are not in excess of —8 volts. This is due to the sharp cut-off characteristic of the amplifier section 40 of the indicator tube, the amplifier section having a high mu. Hence, when the value of the AVC bias applied to the input grid of a 6E5 tube is in excess of —8 volts, the shadow angle on the target remains closed. There is no further indication 45 of approach to the desired resonance condition of the receiver. To solve this problem the 6G5 type tube was provided. This tube differs from the 6E5 type only in that it is provided with a remote cut-off input grid. However, while permitting 50 the tube to be used in receiving circuits

with AVC voltages in excess of —8 volts, the change in shadow angle with grid bias is small at low AVC voltages.

A tube of this same type would be desirable as a balance indicator or as a comparison device for 5 comparing the voltage or current conditions in two different circuits. Previous balance indicators have usually required the use of two separate meters or indicators connected in different 10 circuits requiring duplication of instruments and circuits. In such an arrangement, due to the bulk of the measuring instruments, vision must be shifted from one indicating device to another, increasing the possibility of errors of comparison.

Accordingly, it is one of the principal objects 15 of this invention to provide an electron discharge device of the type described capable of functioning as a reliable indicator of a wide range of input direct current voltages.

More specifically an object of the invention is 20 to improve electron discharge devices of the type adapted to produce an electron shadow of varying width as the magnitude of the direct current voltage input varies; the improvement comprising 25 independent high mu and low mu amplifier sections constructed and arranged to produce opposed shadows on the target, and which shadows successively become narrow as the input voltage varies over a wide range of values.

Another object of my invention is to provide an 30 electron discharge device of the type described which can function as a comparison device or balance indicator for indicating variations of current or voltage in two circuits to be compared, the improvement comprising independent electrode structures arranged to produce opposed 35 shadows on the target, the difference in the shadows or the absence or presence of shadows indicating balance or unbalance of the circuits being compared.

40 Other objects of the invention are to improve generally the efficiency and utility of electron discharge devices of the type described.

The novel features which we believe to be characteristic of our invention are set forth in particularity in the appended claims; the invention itself, however, as to both its organization and method of operation will best be understood by reference to the following description taken in connection with the drawing in which we have 45 indicated diagrammatically a circuit organization whereby our invention may be carried into effect.

In the drawing:

Figure 1 is a circuit diagram of a portion of a receiving circuit and schematic diagram of an 50 55

electron discharge device embodying the invention,

Figures 2a, b, c and d show the successive appearance of the indicator face of the target as 5 the AVC voltage varies in magnitude.

Figure 3 is a schematic section of a modification of an electron discharge device made in accordance with my invention, and

Figures 4a, b and c show the appearance of the 10 indicator face of the target under different conditions when used as a balance indicator or comparison device.

In the circuit shown in Figure 1 a diode detector, or rectifier, 1 has its anode 2 and 15 cathode 3 connected to opposite sides of the secondary winding 4 of the double tuned transformer 5. The primary circuit 6, as well as the secondary circuit 4, is tuned to the operating I. F., assuming the detector is used in a superhetero- 20 dyne receiver. The usual networks are employed in the latter, i. e., a tunable radio amplifier, a tunable first detector, a tunable local oscillator and one, or more, I. F. amplifiers. The customary uni-control tuning adjusting means will 25 be used for varying the rotors of the variable tuning condensers, and the circuit 6 is to be understood as being in the plate circuit of the last I. F. amplifier tube. These networks are not shown since those skilled in the art are fully 30 aware of the construction thereof.

The diode circuit includes resistor 7, shunted by I. F. bypass condenser 8. The grounded cathode 3 is connected to the low alternating potential side of input circuit 4 through the resistor 7. 35 The audio voltage component of detected I. F. current is impressed on one, or more, audio amplifiers by means of the adjustable tap 9 and audio coupling condenser 10. A reproducer of any desired type follows the last audio amplifier. 40 The direct current voltage component of detected I. F. current is employed for automatic volume control (AVC) of the pre-second detector stages, as, for example, the radio and I. F. amplifiers. The AVC lead is connected to the anode side of 45 resistor 7 through filter resistor 11, and bypass condenser 12 to ground. The network 11-12 is given the proper time constant to permit the AVC circuit to compensate for carrier fading effects.

50 In the embodiment of my invention shown in Figure 1, the tuning indicator tube comprises an envelope 13 within which are disposed the electrodes of the indicator section, and the high and low mu direct current amplifier sections. The 55 tube is schematically represented since its detailed constructional features are shown in the Wagner patent referred to above. Those skilled in the art will readily be able to construct a tube embodying the present invention by modifying 60 the tube of said Wagner patent in the light of the present teachings.

The tube is provided with a cathode 13 of the conventional, indirectly-heated, equipotential type; a grid 14 is concentric, and almost co-extensive, with and surrounds the cathode. A pair of anodes 15 and 16, of the same diameter, are co-axially arranged in spaced relation and surround the grid 14. The anodes 15 and 16 are substantially co-extensive with the cathode 13. 65 The portion of grid 14 lying between cathode 13 and anode 16 has at least one turn less than the grid portion between anode 15 and cathode 13. By way of illustration it will be seen that there 70 are five grid turns between anode 15 and cathode 75 13, whereas only four grid turns are provided be-

tween cathode 13 and anode 16. The control grid 14 is wound with a continuous pitch, turns being removed from one end to impart a lower mu to that section of the grid. Hence, it will be seen that a pair of triode sections are provided, 5 one having a higher mu than the other.

The cathode 13 is extended upwardly and provided with a second emitting section 17. A second separate cathode unit could be used. A pair of similar control electrodes 18 and 18' are disposed on opposite sides of emission section 17. The electrodes 18-18' may be rods, or vane-shaped sheet material placed edgewise to the cathode 17. Surrounding and concentric with the emission section 17 is an anode 19 shaped like 15 a dishpan having a coating 20 on its inner inclined face; the coating material being fluorescent under electron bombardment. An aperture is provided in the base of the anode or target 19 to permit the emission section 17 and electrodes 20 18-18' to be positioned at the axis of the anode.

The electrode 18 is connected by lead 21 to plate 15, while electrode 18' is connected to plate 16 by lead 22. Electrons emitted from section 17, and striking coating 20 with sufficient velocity, 25 cause it to fluoresce. A cap (not shown) is usually provided over the top end of cathode section 17 to confine electron action, and to act as an electrostatic shield against stray charges on the glass envelope. The electrons travel radially 30 outwardly from the cathode 17 to the coating 20 in a wide beam. The extent of the anode surface reached by the beam is determined by the direct current voltages on control electrodes 18-18'. Two separate luminescent portions will be obtained when the receiver is off tune. The pattern of light will extend around the entire circumference of anode 19 when the receiver is tuned to resonance.

The control electrodes 18-18' are at positive 40 potentials with respect to cathode 17. This is accomplished by connecting plates 15 and 16 to a source of positive direct current voltage; resistor 23 connecting plate 16 to the positive terminal of the voltage source, and resistor 24 connecting plate 15 to the said terminal. The cathodes 13 and 17 are at ground potential, and fluorescent anode 19 is connected to the positive terminal of the direct current voltage source. A direct current connection establishes control 50 grid 14 at the potential of the anode side of resistor 7. Thus, the AVC bias varies the potential control grid 14, and hence the potentials of control electrodes 18-18'.

In the absence of received signals there is no 55 AVC bias produced, since the detector 1 does not produce detected signal currents. In that case, the control grid 14 will be substantially at the potential of cathode 13, and the current flow through the high and low mu sections will be a 60 maximum. This means that the voltage drops across resistors 23 and 24 will be a maximum, and, therefore, control electrodes 18 and 18' will be at minimum positive potential with respect to grounded cathode 17. As a result of this low 65 positive bias on both control electrodes, electrons will be repelled from the latter, and the pattern shown in Figure 2a will be formed on the coating 20.

The shaded areas in Figure 2a represent the 70 luminous areas, while the blank areas denote shadows. Electrode 18 produces the so-called "high mu shadow" since this electrode varies in bias with space current variation in the high mu triode section of the tube; electrode 18' produces 75

the "low mu shadow" since it responds in bias to the space current change in the low mu triode section. Figure 2a, further, shows the appearance of anode 19 when viewed from the right side of the tube in Figure 1. The dark, or shadow, spaces are depended upon to indicate resonance conditions of the receiver.

Assume, now, that weak signals are received, and a small amount of AVC bias is generated. 10 The space current flowing through the high mu section of grid will be reduced immediately. The shadow angle of the high mu shadow on anode 19 begins to close. At some low bias (-5 to -8 volts) determined by the pitch of the high mu grid, the shadow angle becomes zero. This condition is shown in Figure 2b. Up to this point only a small change in the angle of the low mu shadow has taken place.

Further increase in AVC bias causes the 20 shadow angle of the low mu section to close. Figure 2c shows the appearance of the anode 19 when the low mu shadow is near cut-off. The bias at which the low mu shadow angle is zero can be made equal to -30 to -40 volts depending upon the maximum AVC voltage available. 25 Figure 2d shows the latter condition. Accordingly, it will be seen that the indicator tube of the present invention is capable of responding to a relatively wide range of AVC voltages, and that 30 this is done with a single tube construction.

By proper choice of the structural dimensions of the tube and triode section plate loads, conditions can be adjusted so as to cause the two shadows to respond to any reasonable AVC voltage ranges. 35 Of course, Figure 2a shows the appearance of the tube when off tune, or when very weak carrier is being received. Figure 2d, on the other hand, shows the tuning indicators appearance when the receiver is exactly tuned 40 to a strong incoming carrier. Intermediate conditions are shown by Figures 2b and 2c.

In Figure 3 the electron discharge device is provided with the two-section cathode 13 surrounded by anodes 15 and 16 axially displaced 45 along one emitting section of the cathode and connected to the control electrodes 18' and 18 positioned between the other section of the cathode 13 and the fluorescent target or anode 19. The indicator and amplifier sections could be 50 made as separate units each having its own cathode. In accordance with my invention each of the anodes 15 and 16 has positioned between it and the cathode a separate control grid 25 and 26. Difference in potential between the control 55 electrodes 18 and 18' and the fluorescent anode is produced in the same manner as in the device shown in Figure 1 by means of the drop in the resistors 23 and 24. The grids 25 and 26 may have the same pitch, or, if desired, different pitch. 60 The voltage sources to be compared are connected to the leads 27 and 28 connected to the separate grids 25 and 26. The tube functions in substantially the same way as that shown in Figure 1. The difference in the circuits being 65 compared is indicated by a difference in the shadows formed on the fluorescent target by the control electrodes 18 and 18'.

The applications of a tube of this type are 70 numerous. In use as a balance indicator the tube is operated with both grids biased to cut-off at balance. The whole target under this condition fluoresces. The change in bias on either of the two grids and the formation and size of the resulting shadows indicate the direction in 75 which the balance is off. One specific applica-

tion of a tube made according to my invention is to a course indicator for airplanes. This can be done by means of a signal, the strength of which is proportional to the amount by which the plane is off the beam along which the plane flies. The 5 signal may be rectified and presented as bias in the proper polarity to the grids of the tube. Thus, when the plane is on the course no shadow appears. This condition is shown in Figure 4a. If the plane drifts to the left a shadow appears as 10 indicated in 4b on the left hand side of the target, and if it drifts to the right a shadow appears on the right hand side of the target as indicated in 4c, the size of the shadow being proportional to the amount the plane is off its 15 course.

While we have indicated and described a system for carrying our invention into effect, it will be apparent to one skilled in the art that our invention is by no means limited to the particular organization shown and described, but that many modifications may be made without departing from the scope of our invention, as set forth in the appended claims.

What we claim as new is:

1. An electron discharge device having an envelope, a cathode within said envelope for supplying electrons, a dish-shaped anode surrounding the cathode and having its interior surface coated with a fluorescent material for receiving electrons from the cathode to produce a luminous annular shaped pattern on the anode, a plurality of control electrodes positioned between the anode and the cathode to determine the area of the fluorescent surface of the anode reached by the electrons, 30 a second cathode in said envelope, a plurality of plates surrounding said second cathode, said plates being axially spaced along said second cathode, and control means between the second cathode and said plates and a conductor connected between each of the control electrodes and a different one of said plates.

2. An electron discharge device having an envelope, a cathode within said envelope for supplying electrons, a dish-shaped anode surrounding the cathode and having its interior surface coated with fluorescent material for receiving electrons from the cathode to produce a luminous annular shaped pattern on the anode, a pair of oppositely disposed control rods positioned between the coated anode and the cathode to determine the area of the fluorescent surface of the anode reached by the electrons, a second cathode, 45 a pair of plates surrounding the second cathode and axially spaced with respect to each other, control means positioned between the plates and the second cathode, each of said plates being connected to a different one of said control rods.

3. An electron discharge tube having an envelope, a cathode within the envelope for supplying electrons, a dish-shaped anode surrounding the cathode and having its interior surface coated with a fluorescent material for receiving electrons from the cathode to produce a luminous annular shaped pattern on the anode, a control 50 electrode positioned between the anode and the cathode to determine the area of the fluorescent surface of the anode reached by the electrons, a second control electrode positioned on the opposite side of the cathode, a second cathode, a 55 grid surrounding the second cathode, a pair of plates surrounding the grid, the plates being of the same diameter and being coaxially spaced, the grid portion between one of the plates and the second cathode having a lesser number of turns 60

than its other portion, and independent direct current connections between the two control electrodes and said plates.

4. An electron discharge device having an envelope, a cathode within said envelope for supplying electrons, a dish-shaped anode surrounding the cathode and having its interior surface coated with fluorescent material for receiving electrons from the cathode to produce a luminous 10 annular shaped pattern on the anode, a plurality of control electrodes positioned between the anode and the cathode to determine the area of fluorescent surface of the anode reached by the electrons, a second cathode, a plurality of separate 15 grids axially spaced with respect to each other and surrounding said second cathode, a plate electrode surrounding each of said grids and independent direct current connections between each of the plates and a different one of said 20 control electrodes.

5. An electron discharge device having an envelope, a cathode within said envelope for supplying electrons, a dish-shaped anode surrounding the cathode and having its interior surface 25 coated with fluorescent material for receiving electrons from the cathode to produce a luminous annular shaped pattern on the anode, a pair

of control rods disposed on opposite sides of said cathode and between said cathode and the anode to determine the area of the fluorescent surface of the anode reached by the electrons, a pair of grids surrounding said cathode and axially spaced 5 with respect to each other and said anode, a plate surrounding each grid, each plate having a direct current connection between a different one of said control rods.

6. An electron discharge device having an envelope, a cathode within said envelope, a dish-shaped anode surrounding the cathode and having its interior surface coated with fluorescent material for receiving electrons from the cathode to produce a luminous annular shaped pattern 15 on the anode, a plurality of control rods positioned between the anode and the cathode and parallel to the cathode to determine the area of fluorescent surface of the anode reached by the electrons, a plurality of separate grids axially 20 spaced with respect to each other and surrounding said cathode, a plate electrode surrounding each of said grids and independent direct current connections between each of the plates and a different one of said control rods. 25

CHARLES N. KIMBALL.
EDWARD W. WILBY.
